UNITED STATES PATENT OFFICE.

EUGENE S. MICHENER, OF NEW CASTLE, PENNSYLVANIA.

INTERNAL-COMBUSTION ENGINE.

1,037,953.

Specification of Letters Patent. Patented Sept. 10, 1912.

Application filed January 27, 1912. Serial No. 673,714.

To all whom it may concern:

Be it known that I, EUGENE S. MICHENER, a citizen of the United States, residing at New Castle, in the county of Lawrence and 5 State of Pennsylvania, have invented certain new and useful Improvements in Internal-Combustion Engines, of which the following is a specification.

The present invention relates to improvements in internal combustion engines, and 10 is specially designed for use in connection with gasolene motors of auto-vehicles.

The object of the invention is the provision of means for admitting additional and 15 auxiliary air to the intake pipe of a gasolene engine between the carbureter and the engine, and for mixing the additional charge of air with the mixed fuel gas as it passes from the carbureter to the engine. The results of admitting this extra charge of air 20 to the intake pipe are numerous and advantageous, in that the efficiency of the charge may be determined with relation to the load without changing the adjustment of the carbureter. For instance, it is well understood 25 in this art that a correct mixture of gasolene and air to develop the greatest possible power under heavy loads, in the engine, is far too rich for light loads, and consequently 30 the proportion of gasolene and air must be varied to suit the different existing conditions. Resort to adjusting the carbureter to suit these conditions is objectionable and undesirable. But with my auxiliary device, 35 the proportion desired in the mixture may be varied in a simple manner without disturbing the carbureter.

The invention consists in certain novel 40 combinations and arrangements of parts in connection with an internal combustion engine as will be more fully described and pointed out in the following.

In the accompanying drawings I have 45 illustrated the invention according to the best mode I have so far devised for the practical application of the principles and such embodiment has proved highly satisfactory in actual use.

Figure 1 is a view of so much of an automobile and gasolene motor as is necessary 50 to illustrate the application of the invention. Fig. 2 is an enlarged view, in side elevation, showing the invention applied to the intake pipe or manifold, above the carbureter. Fig. 3 is a top plan view of Fig. 2,

partly broken away for convenience or illustration, and Fig. 4 is a vertical sectional view of Fig. 2 with the device detached.

In the drawings I have illustrated the invention applied to an automobile motor 1, of well known standard type, to the intake pipe or manifold 2 of which the device is attached. A conventional carbureter 3 is indicated, from which the intake pipe or manifold extends, and is connected with the several engines 4 of the automobile motor.

In the preferred embodiment of my invention I employ a casting, preferably of brass, including the cup 5 formed with a small upper opening 6, and the integral tubular extension or sleeve 7. Located transversely within the sleeve is a valve plug 8, of usual or suitable type, and the stem 9 of the plug is provided with a notched disk 10, positioned outside the sleeve 7. The stem 9, as seen clearly in Fig. 1 extends back from the motor and is passed through the dash board 11 of the automobile, a plate 12 being indicated as a bearing plate. The valve, through its stem, may be turned by means of the handle 13.

The sleeve 7 is fashioned with a reduced extension 14, and the extension is exteriorly threaded and adapted to be screwed into the threaded opening 15 of a saddle 16. Within the open end of the extension 14 is secured a cone shaped screen 17 of suitable wire gauze mesh, and this screen, when in proper position, projects across the bore of the intake pipe 2 as shown in Fig. 3 for instance. The intake pipe is perforated for the reception of the screen, and when the screen is projected across the intake pipe as shown, the entire device is securely held to the intake pipe by means of the bracket or clip 19, whose threaded prongs are passed through the perforated ears 20 of the saddle 16 and secured to the saddle by means of the nuts 21.

The flow of air through the device may be 100 regulated from the handle 13 of the stem 9 and the valve may be held in adjusted position by means of the spring catch or detent 22 which engages the toothed disk 10 on the valve stem. When the valve is open, air 105 passes through the cup 5, valve 8, sleeve 7 and through the screen into the intake pipe. The admission of the air through the screen in the form of a spray, remixes the gasolene 110 globules as they come from the carbureter,

and the charge is thus increased in power, and economy in consumption of gasoline is effected.

For the purpose of priming the gasoline engines, the cup 5 is specially well adapted. When difficulty is experienced in starting the motor, by pouring a few drops of gasoline into the cup 5, it will be found that upon cranking the motor, with the valve 10 open say two notches, the engine will be effectively primed for starting.

When coasting down-grade, with the ignition cut off, the valve 8 may be entirely open, but the throttle closed, the suction of the engines draw the pure air through the cup and valve into the cylinders, thus permitting the motor to act as a brake as will be understood, and effecting a thorough cooling of the cylinders.

One of the serious problems to overcome in the use of devices of this character is to pass the charge to the cylinders with the minimum resistance. But by using my device it is possible to reduce the air resistance to a minimum without sacrificing the starting or low speed adjustment of the carbureter, and compensation for altitude may be readily made without disturbing the pre-arranged carbureter adjustment.

Having thus fully described my invention, what I claim and desire to secure by Letters Patent is:—

1. The combination with the perforated intake pipe of a gasoline engine, of a sleeve 35 opening into said perforated pipe, a screen closing the sleeve end and located within said pipe, a valve in the sleeve, and an open cup integral with said sleeve, means for securing the sleeve to said pipe, and means for 40 controlling said valve.

2. The combination with the perforated intake pipe of a gasoline engine, of a sleeve

having a reduced threaded extension opening into said pipe, a saddle perforated and threaded to receive said extension and formed with perforated ears, a clip having its ends secured in said ears for attaching the saddle to the pipe, a conical screen on the extension located inside the pipe, and a valve and actuating means therefor in said sleeve.

3. The combination with the perforated intake pipe of a gasoline engine, of a sleeve having a reduced threaded extension, a perforated saddle attached to the pipe to receive said extension, a conical screen on the extension in the pipe, a valve in said sleeve, a valve stem, a notched disk on said stem, and a spring detent engaging said disk.

4. The combination with the perforated intake pipe of a gasoline engine, of a sleeve with a threaded extension, a perforated saddle attached to the pipe to receive said extension, a conical screen on the extension in the pipe, a valve in said sleeve, a valve 65 stem, a notched disk on said stem, a spring detent engaging said disk, and an integral cup forming part of said sleeve.

5. The combination in a device as described of a sleeve, a valve and valve stem to control the opening therethrough, a notched disk on said stem, a spring detent engaging said disk, a cup integral with the sleeve and having a reduced opening, a threaded attaching extension on said sleeve, 75 and a conical gauze screen closing the opening of said extension.

In testimony whereof I affix my signature in presence of two witnesses.

EUGENE S. MICHENEN.
